UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

DESIGN FOR A KNIFE-HANDLE.

SPECIFICATION forming part of Design No. 25,561, dated June 2, 1896.

Application filed April 24, 1896. Serial No. 588,979. Term of patent 7 years.

To all whom it may concern:

Be it known that I, CHARLES F. SMITH, a citizen of the United States, residing at New Britain, in the county of Hartford and State of Connecticut, have invented and produced a new and original Design for Cutlery-Handles, of which the following is a specification, reference being had to the accompanying drawings, in which—

10 Figure 1 is a side elevation of a knife-handle, showing my design. Fig. 2 is a plan or edge view of the same.

My handle comprises a tang 3 of a knife or fork, the bolster 4, tip 5, and scales 6. It is 15 oval in cross-section or end view and slightly tapering in side view, being the broadest at the butt.

The middle portion of the handle-scales is

ornamented by an inlaid ornament consisting of a central hub 7, a circular bar or ring 8 ²⁰ concentric therewith, central and diametrical longitudinal arms or bars 9 ⁹, and transverse arms or bars 10 ¹⁰ intersecting said ring, as shown.

The arms, although best seen when the handle presents a side view, partially show when the handle is seen in plan or edge view, as in Fig. 2.

What I claim is—

The design for a cutlery-handle substantially as shown and described.

CHARLES F. SMITH.
